DESIGN FOR A DISPENSING MACHINE CABINET

Lawrence M. Persons, St. Louis County, Mo.

Application December 2, 1938, Serial No. 81,520

Term of patent 14 years

To all whom it may concern:

Be it known that I, Lawrence M. Persons, a citizen of the United States, residing in St. Louis County, State of Missouri, have invented a new, original, and ornamental Design for a Dispensing Machine Cabinet, of which the following is a specification, reference being had to the accompanying drawing forming a part thereof, in which:

The figure is a perspective view of a dispensing machine cabinet, showing my new design.

Characteristic features of the present design reside in the panelling set off by suitable dividing strips, the rectangular push buttons, and the contour of the upper section.

I claim:

The ornamental design for a dispensing machine cabinet, substantially as shown and described.

LAWRENCE M. PERSONS.
